UNITED STATES PATENT OFFICE.

CHRISTIAN VESTERGAARD, OF CHICAGO, ILLINOIS.

SHEARS.

1,183,919.

Specification of Letters Patent. Patented May 23, 1916.

Application filed October 30, 1912. Serial No. 728,550.

To all whom it may concern:

Be it known that I, CHRISTIAN VESTERGAARD, a citizen of the United States, and a resident of the city of Chicago, county of Cook and State of Illinois, have invented certain new and useful Improvements in Shears, of which the following is a specification.

My invention relates to improvements in manually operable shears especially designed for use in cutting leather, rubber and sheet iron, and has for its object, the production of a shear of this character, which will be of extremely simple and economical construction, and efficient in use.

Other objects will appear hereinafter.

The invention consists in the combinations and arrangements of parts hereinafter described and claimed.

The invention will be best understood by reference to the accompanying drawing forming a part of this specification, and in which,

Figure 1 is a perspective view of a shear embodying my invention, Fig. 2 is a top plan view thereof, and Fig. 3 is an enlarged vertical transverse section taken on line $x-x$ of Fig. 2.

The preferred form of construction as illustrated in the drawing comprises a base member 1 which is angular in cross section, consisting of a base or horizontally extending flange 2 and a vertically extending flange 3. The flange 2 is perforated for the accom-

modation of bolts or other suitable securing devices 4 for securely fastening base member 1 upon a table top or other suitable place or support. Arranged upon one side of the vertically extending flange 3 is a relatively

stationary blade 5, said blade being removably secured to the flange 3 by means of screws 6 which are threaded into said flange, the heads of said screws being counter-sunk in the outer face of said blade so as to be

flush therewith for obvious reasons. Formed at the base of the flange 3 is a shoulder 7 positioned for contact with the back or lower edge of the blade 5 in order to reinforce the same and relieve the strain

upon screws 6, it being clear that in the operation of the shear the strain or pressure upon blade 5 will be downwardly. Coöperating with the base member 1 is an elongated lever 8 one end of which is fulcrumed

to the corresponding end of flange 3 of base member 1 by means of a bolt 9 and nut 10.

Carried by the lever 8 is a relatively movable blade 11 which is removably secured to said lever by means of screws 12 threaded into said lever, the heads of said screws being counter-sunk in the outer face of said blade so as not to interfere in the shearing operation as will be readily understood. Formed upon the lever 8 is a shoulder 13 which coöperates with the back edge of the blade 11 in the same manner as the shoulder 7 coöperates with the blade 5, as above set forth.

In using the device it is only required to engage the outer end of lever 8 and oscillate the same, such oscillation of said lever effecting the operative movement of the blade 11 to effect the shearing or cutting of the work arranged between the said blade and the relatively stationary blade 5. The blades 5 and 11 are curved, as shown in Fig. 2 so that their concave sides contact with each other, such curvature of said blades insuring close engagement of the cutting edge thereof and hence the effective shearing or cutting operation when the device is in use. By removably securing the lever 8 to the base member 1, and by removably securing the cutting blades to said lever and base member, the device may be readily disassembled in order to permit of ready sharpening of the blades or of the replacement thereof. Sharpening of the blades may, however, be effected without removal of the same from the base member or lever since the cutting edges thereof are readily accessible for contact with an emery wheel, grindstone or other sharpening or abrasive element.

The shear is simple and economical in construction and hence may be manufactured at a low cost.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claim.

Having described my invention what I claim as new and desire to secure by Letters Patent is:

A shear of the class described, comprising a stationary base member angular in

cross section consisting of a horizontal and vertically extending flange, a relatively stationary blade arranged on said vertically extending flange, co-extensive in length therewith, and projecting above the upper edge thereof, said vertical flange having a shoulder supporting the lower edge of said blade, an upwardly extending ear on one end of said flange, a pivot bolt extending through said ear and said blade, a lever, a relatively movable blade fixed to said lever, said bolt extending through said lever and

said movable blade adjacent one end thereof and said lever being provided with a shoulder engaging the upper edge of said blade, substantially as described.

In testimony whereof I have signed my name to this specification in the presence of two subscribing witnesses.

CHRISTIAN VESTERGAARD.
